ENVELOPE FASTENER MACHINE

Abraham Novick, Flushing, N. Y., assignor to
F. L. Smithe Machine Co., Inc., New York,
N. Y., a corporation of New York

Application July 7, 1937, Serial No. 152,295

20 Claims. (Cl. 93—61)

This invention relates to a machine for applying to the walls of envelopes attachments of various sorts, such as clasp fasteners of the type illustrated in Letters Patent No. 1,827,901, issued to me on October 20, 1931, these fasteners being each formed out of a single piece of sheet metal of approximately cruciform shape, comprising elongated tongues extending in opposite directions from a central web, with attaching lobes extending in opposite directions from the same web, preferably at right angles to the major axis defined by the tongues.

Machines are known for attaching such fasteners to the back walls of envelopes, so disposed that when the tongues are bent up out of the plane of the envelope toward each other, they may be passed through a hole in the cover-flap and then bent back over the margins at opposite sides of the hole to retain the cover-flap in closed position.

The present invention constitutes an improvement upon this type of machine, and may be embodied in various machines of the type, as for example such a machine as that disclosed and claimed in my copending application, Serial No. 142,393, parts of which are hereinafter illustrated in somewhat schematic form to aid in the understanding of the present invention.

An object of this invention is to provide a machine for applying a fastener of the above type to each of a multiplicity of envelopes which are supplied from a stack of such envelopes having their cover-flaps initially folded over and thus closed, this being an advantageous condition in which to stack the envelopes, by reason primarily of the evenness with which they may be disposed during transportation, storage and in the stack.

A further object of the invention is to provide a machine with means for opening each cover-flap in preparation for application of the fastener to the envelope body; and also in preparation for the attachment thereto of a patch, and for perforation of the flap and patch to provide an orifice reinforced by the patch and in proper position to cooperate with the fastener.

Still another object is to provide such a machine with a mechanism for closing each cover-flap after completion of the attachment operations, which mechanism may be added when it is desired to deliver the envelopes in closed condition.

Other objects and advantages of the invention forming the subject of the present application will appear as the description of the particular

physical embodiment of the invention selected for illustration and description progresses.

In the accompanying drawings, like characters of reference have been applied to corresponding parts throughout the several views which make up the drawings, in which:

Fig. 1 is a view of a schematic character, in vertical sectional elevation, of a fastener-applying machine in the construction of which the present invention has been embodied;

Fig. 2 is a plan view of a completed envelope with a fastener applied thereto by the machine herein disclosed; and provided with a patch-reinforced perforation in the cover-flap;

Fig. 3 is a view, of a schematic character, showing in plan certain of the operating parts illustrated in Fig. 1;

Fig. 4 is a schematic view in plan, complementary to Fig. 3, and in which is shown a run of mechanism for reclosing the cover-flaps.

In a now preferred embodiment of the invention selected for illustration and description, referring first to Fig. 1, the parts designated by the reference characters B' and B'' are the belts of an endless conveyor, around which the means for performing the operations which characterize the present invention are organized. This belt conveyor runs upon pulleys 41 and 42, the latter of which is driven by a countershaft 43 actuated by the main driving shaft 1 through bevel gears 44—45 (see Fig. 4).

At the left of Fig. 1 is shown a means for supplying to the conveyor a series of envelopes E, E', etc., derived successively from a stack S thereof, supported suitably as by plates 11, and from the bottom of which stack each envelope which at any time constitutes the lowermost or innermost component of the stack, is transferred from the stack to the conveyor belts B', B'' preferably by the improved transfer mechanism illustrated in Fig. 1.

In the instance illustrated, two rotary elements R' and R'' spaced apart on the shaft 30, (see Fig. 3) are each provided with a gripper member G (see Fig. 1) each of which is mounted pivotally in the periphery of its rotor, upon which it can be oscillated, as by means of a cam C, shown in my above mentioned application, to grip the free or leading end 12 of the then lowermost blank, when the latter is separated from the stack. This separation, and the details of devices by which it may be conveniently effected, are also illustrated fully and described at length, in my aforesaid copending application, and a brief summary of the mechanism will now suffice.

Such separation is effected by a sucker S' mounted upon a bail 20 which is swung about an axis 21 on a suitable support not shown herein.

It will be readily understood by those skilled in the art that when the rotors R' and R'' are rotated, and when the grippers G have been engaged with the leading edge 12 of the envelope separated by the sucker S' and moved toward the rotors, the grippers draw each envelope E around the periphery of the rotors, and the bottom, closed leading end 12 of the envelope will be entrained in due time between the rotors R' and R'' and the conveyor belts B' and B'' whereupon the suction will be cut off in known fashion by suitable means (not shown).

Upon movement of the conveyor belts in the direction of the arrow (Fig. 1) they advance the envelope just received from the rotors until the leading end 12 is arrested, as by a pair of stops 53 and 54 , which are moved upward into the path of the advancing envelope by suitable means, illustrated as a block 55 , which is operated by mechanism to be described.

Before description of the attachment operations which are to be effected upon the envelope, the operation of opening the cover-flap will first be described, since it is of the essence of the present invention to accomplish such opening, the envelopes being stacked with their cover-flaps initially closed as already noted.

It is not essential, however, that the opening operation shall be effected in the preferred manner now disclosed, which is merely illustrative, possessing certain advantages which will be made to appear, and for that reason constituting the best method for the purpose now known to applicant.

Referring to Fig. 1, it will be seen that the natural resiliency of the foremost cover-flap 10 is usually sufficient to cause a degree of protrusion therefrom from the body of the envelope which aids in its complete opening, for example by the use of an interference member such as that shown at 16 , and the upper edge $16x$ of which is suitably positioned to be engaged with the free edge of the flap as soon as the envelope begins to descend, drawn downward by the rotors R' , R'' as already described.

When so stripped backwardly, no further opening means is required, but in the event that the cover-flap happens not to project sufficiently far to insure such entry of the interference member, another and auxiliary means may be provided to effect a positive outward draft upon the free forward edge of the cover-flap 10 , to position it for engagement therebeneath by the interference member.

Any suitable means may be utilized for that purpose, and as one suitable and convenient form of stripper means, use may be made, as illustrated, of another sucker device Sx , which will preferably be disposed at approximately the region illustrated in Fig. 1, where it is shown as adapted to swing to and fro, into and out of engagement with the leading margin of the cover-flap 10 . Suction may be cut off from it after a very slight outward pull, as it is only necessary to assure the requisite projection of the free edge of the flap 10 beyond the upper edge of the interference membr $16x$.

Reverting now to the further travel of the envelope, and the operations which are to be performed thereupon while the cover-flap is in its opened condition, the present disclosure contemplates the performance of a patch-applying op-

eration and a patch-perforating operation at a suitable station, as at A'' , (see Fig. 1); and concurrently the performance of a fastener-applying operation, as at the station designated generally by the reference character A' . No description of these operations in detail need be made herein, inasmuch as they are merely illustrative of a variety of such attachment or other operations, and a full description of the preferred form of mechanism by which they may be effected is to be found in my co-pending application Serial No. 142,393, to which reference has already been made.

It will therefore be sufficient to say that the envelope is first fed beneath the anvil V up to the point of its arrest by the fingers 53 , 54 , as in Fig. 3, which have been raised into the path of the envelope by the action of a lever 59 cooperating with a rail 67 on which is mounted the block 55 that carries the fingers 53 , 54 . The lever 59 is pivotally mounted at 60 upon a post 61 , and has an arm 63 with a follower 64 engaged with a cam 65 upon the driving shaft 1 , and this cam acts to retract the fingers positively to their position shown in full lines in Fig. 1. A spring 58 , exerts a bias normally tending to raise the fingers to the dotted line position in the path of the envelope.

Fasteners are supplied to the fastener-applying station A' through a chute C , as described in my above mentioned copending application, Serial No. 142,393, and are clinched in the usual, or any suitable manner. Patch strip S'' is fed in the manner described in said application and is moistened at $131x$; being then fed by rolls 131 and 132 through a trough 165 to the station A'' ; is there severed suitably and is pressed down upon the flap 10 , and perforated with the flap, all as described in said application, or in any suitable manner, after the anvil V has been advanced from the position shown in full lines in Fig. 3, to a position in which it is aligned with the plunger A , and in which it clears the patch applying plunger 128 , and enters the open end of the envelope.

Suitable means are provided, as at 32 , (see Fig. 3) to cause adequate opening of the walls of the envelope to receive the anvil, the finger 82 being raised momentarily to buckle the walls and then being retracted positively by the action of a lever 86 rocked for that purpose by the cam C'' upon the driving shaft 1 .

The advance and retraction of the anvil V are accomplished through the arm V' by a carriage 200 , sliding in ways 201 , and pushed forward by a link 102 spring-biased to its forward position, the retraction of the anvil being performed positively by the action of a cam $C3$ fixed upon the countershaft 3 , and engaged with a follower 107 carried by a pitman 104 connected to the link 102 .

This mechanism is all fully described in my aforesaid co-pending application.

In pursuance of another object of the invention, which is to provide a mechanism which may be added to the above machine, and by which the cover-flap of each envelope may be closed, after the fastener-applying and patch-applying operations, when it is desired to deliver the envelopes in closed condition, the envelopes are again advanced. This is done as soon as each is released from arrest by retraction of the fingers 54 and 53 from the path of feed, the envelopes being then free to have their advance resumed by the belts B' and B'' , which are ar-

ranged, in the instance illustrated, to deliver the envelopes seriatim to a suitable flap-closing run of mechanism.

This mechanism, designated generally by the reference character M_x , is shown in Fig. 4, the left-hand side of this figure conforming with the right-hand side of Fig. 3 of the drawings, and the actuation of the mechanism therein shown being accomplished by means of a countershaft $43x$ 10 driven through bevel gears by the shaft 43 which drives the belts B' and B'' .

The shaft $43x$, in turn, drives a pair of sprockets $41x$, from which chains $B3$ stretch to rollers $42x$ on an idler shaft $40x$, these chains 15 running past a transfer station designated generally by the reference character $T2$, where the envelopes are delivered individually transversely of the chains $B3$.

Correct alignment is provided for by an abutment M' , along which the leading end 12 of each envelope is carried in turn as the envelopes, with their cover-flaps still open, are moved from the transfer station, at right angles to their original path. Preferably the chains $B3$ are provided with 25 studs $44x$ to insure maintenance of the envelopes in correct alignment and their positive travel to the end of the run M_x , where they may conveniently be accumulated in a stack SE .

The operation of closing the flaps may be accomplished during this run, and by any suitable mechanism, of which a convenient form is that illustrated in Fig. 4, at F , which shows a conventional type of folder rail, having a generally ogee shape and with which cooperates a table or bar Fx to turn the flap around the fold line 7 and dispose it snugly against the body of the envelope, in known fashion, as indicated at $10x$ in Fig. 4. Rollers R or other suitable devices may be employed to hold the envelopes, while in transit, 40 against the chain $B3$.

In order to aid in completing the transfer of each envelope from the run defined by belts B' , B'' in Fig. 4, to the run defined by belts $B3$ provision is preferably made of suitable means which 45 may desirably take the form of a friction roller as 154 , in position to be engaged with the lower broadside face of each envelope as they pass successively over the opening 155 formed in an elongated plate 156 disposed between the belts $B3$.

The roll is suitably driven, as by a counter belt 151 , running between pulleys 150 and 152 respectively and exerts a bias tending to advance each envelope into contact with the abutment M' .

A spherical, self-weighted pressure member 157 55 may desirably be provided, in a central position over the intersection between the axes of the runs of mechanism, to aid in maintaining contact between the envelope and the underlying roll 154 . A suitable socket (not shown) may be provided to hold the sphere loosely, so that it may roll freely on the upper face of each envelope as they approach the intersection in one direction, and depart therefrom at right angles to that direction.

From the foregoing disclosure the various steps involved in the operation of attaching clasp-fasteners and protective patches to envelopes in a machine to which the envelopes are supplied in initially closed condition will be readily understood.

The operation of the machine may be summarized as follows:

From a supply of the envelopes in a stack S , with their flaps closed, the envelopes are withdrawn individually, lengthwise, with their sealed

bottom edges 12 leading, these edges being separated, one by one, as each envelope reaches the foremost position, where its lower margin is sucked out by the sucker S' and caused to approach the rotors R', R'' .
5

The grippers G then seize the edge 12 , and draw the envelope forward lengthwise, and during this initiation of the travel by the envelope in its own plane, the flap 10 is projected outward from said plane, either by its own resilience or by 10 the action of an auxiliary separator device, such as the sucker Sx .

The free edge of the flap is thus hooked over the interference member $16x$ which completes the opening of the flap, and then the envelope is 15 drawn around and delivered to the chains B', B'' which advance it to the stops $53, 54$, by which it is arrested for the patch-applying and the fastener-attaching operations, at the stations A' and A'' .
20

After these operations, the stops $53, 54$ are retracted downwardly, permitting the envelope to resume its advance under the action of belts B', B'' which then may deliver it to a suitable container if the envelopes are to remain open or 25 to the mechanism M_x , if they are to be closed again, in which latter event the belts $B3$ receive the envelope, close the flap 10 , and deliver it to the stack SE .

I have described what I believe to be the best 30 embodiments of my invention. I do not wish, however, to be confined to the embodiments shown, but what I desire to cover by Letters Patent is set forth in the appended claims.

I claim:

1. A machine for applying an attachment, such as a fastener and/or a patch, to an envelope with a cover-flap, in an operation to be performed while said cover-flap is open; said machine comprising, in combination, means to supply envelopes with initially closed cover-flaps; an attachment-applying station; means to open the cover-flap of each envelope; means to advance an envelope toward said station after having opened its cover-flap; and means to apply an 40 attachment to said envelope at said station while said cover-flap is open.
45

2. A machine for applying an attachment, such as a fastener and/or a patch, to an envelope with a cover-flap, in an operation to be performed 50 while said cover-flap is open; said machine comprising, in combination, means to supply envelopes with initially closed cover-flaps; an attachment-applying station; means to open the cover-flap of each envelope; means to advance 55 an envelope toward said station after having opened its cover-flap; means to apply an attachment to said envelope at said station while said cover-flap is open, and means to close said cover-flap.
60

3. A machine for applying attachments, such as fasteners and/or patches, to envelopes with cover-flaps, in a series of operations to be performed while said cover-flaps are open; said machine comprising, in combination, an attachment-applying station; means to support a supply of envelopes with closed cover-flaps; means to open each cover-flap; means to advance said envelopes seriatim toward said attachment-applying station when their respective cover-flaps 70 have been opened; means to apply an attachment to each of said envelopes at said station while the cover-flap is open; means to close said cover-flaps respectively; and means to accumulate said envelopes in stack formation.
75

4. A machine for applying an attachment, such as a fastener and/or a patch, to an envelope with a cover-flap, in an operation to be performed while said cover-flap is open; said machine comprising in combination, means to supply envelopes with initially closed cover-flaps; an attachment-applying station; means to open the cover-flap of each envelope; means to advance an envelope toward said station after having opened its cover-flap; and means to apply an attachment to said envelope at said station while said cover-flap is open, said flap-opening means including a device adapted to be engaged with said flap in transit. 5
5. A machine for applying an attachment, such as a fastener and/or a patch, to an envelope with a cover-flap, in an operation to be performed while said cover-flap is open; said machine comprising in combination, means to supply envelopes with initially closed cover-flaps; an attachment-applying station; means to open the cover-flap of each envelope; means to advance an envelope toward said station after having opened its cover-flap; and means to apply an attachment to said envelope at said station while said cover-flap is open, said flap-opening means including a device adapted to be engaged beneath the leading edge of said flap in transit. 10
6. A machine for applying an attachment, such as a fastener and/or a patch, to an envelope with a cover-flap, in an operation to be performed while said cover-flap is open; said machine comprising, in combination, means to supply envelopes with initially closed cover-flaps; an attachment-applying station; means to open the cover-flap of each envelope; means to advance an envelope toward said station after having opened its cover-flap; and means to apply an attachment to said envelope at said station while said cover-flap is open, said flap-opening means including a device adapted to be engaged with the outer face of said flap, and to cause divergence of the flap from the body of the envelope at the fold-line of said cover-flap and body. 15
7. A machine for applying an attachment, such as a fastener and/or a patch, to an envelope with a cover-flap, in an operation to be performed while said cover-flap is open; said machine comprising in combination, means to supply envelopes with initially closed cover-flaps; an attachment-applying station; means to open the cover-flap of each envelope; means to advance an envelope toward said station after having opened its cover-flap; and means to apply an attachment to said envelope at said station while said cover-flap is open, said flap-opening means including a device adapted to be engaged with the outer face of said flap while in transit, and to cause divergence of the flap from the body of the envelope at the fold-line of said cover-flap and body. 20
8. A machine for applying attachments, such as fasteners and/or patches, to envelopes in a series of operations to be performed while their cover-flaps are open; said machine comprising, in combination, an attachment-applying station; means to support a stack of envelopes assembled upon their closed bottom edges with their cover-flap ends extending upwardly in partly closed position; means to separate the lowermost closed edge of each envelope from the stack, said separating means including a sucker device; means to advance each envelope after such separation of its leading edge; means to open each cover-flap when the envelope is so advanced; means to apply an attachment to each envelope at said station; and means to accumulate said envelopes in stack form. 25
9. A machine for applying attachments, such as fasteners and/or patches, to envelopes with cover-flaps, in a series of operations to be performed while said cover-flaps are open; said machine comprising, in combination, an attachment-applying station; means to support a stack of envelopes assembled upon their closed bottom edges with their cover-flap ends extending upwardly in partly closed position; means to separate the lowermost closed edge of each envelope from the stack, said separating means including a sucker device; means to advance each envelope after such separation of its leading edge; means to open each cover-flap when the envelope is so advanced, said opening means including another sucker device operating exclusively upon each cover-flap, means to apply an attachment to each envelope at said station; and means to accumulate said envelopes in stack form. 30
10. A machine for applying an attachment, such as a fastener and/or a patch, to an envelope with a cover-flap, in an operation to be performed while said cover-flap is open; said machine comprising, in combination, an attachment-applying station; means to receive a supply of envelopes having initially closed cover-flaps; means to advance said envelopes toward said station; means to open each cover-flap in transit to said station; and means to apply an attachment to each envelope at said station while its cover-flap is open. 35
11. A machine for applying an attachment, such as a fastener and/or a patch, to an envelope with a cover-flap, in an operation to be performed while said cover-flap is open; said machine comprising, in combination, an attachment-applying station; means to receive a supply of envelopes having initially closed cover-flaps; means to advance said envelopes toward said station; means to open each cover-flap in transit to said station; means to apply an attachment to each envelope at said station while its cover-flap is open, and means to close said cover-flaps respectively. 40
12. A machine for applying attachments, such as fasteners and/or patches, to envelopes with cover-flaps, in a series of operations to be performed while said cover-flaps are open; said machine comprising, in combination, an attachment-applying station; means to support a supply of envelopes with closed cover-flaps; means to advance said envelopes seriatim toward said attachment-applying station with their respective cover-flaps initially closed; means to open each cover-flap while its envelope is in transit to said station; means to apply an attachment to each of said envelopes at said station while its cover-flap is open; means to close said cover-flaps respectively while said envelopes are in transit from said station; and means to accumulate said envelopes in stack formation. 45
13. A machine for applying an attachment, such as a fastener and/or a patch, to an envelope with a cover-flap, in an operation to be performed while said cover-flap is open; said machine comprising, in combination, means to supply envelopes with initially closed cover-flaps; an attachment-applying station, means to open the cover-flap of each envelope; means to advance an envelope toward said station after having opened its cover-flap; and means to apply 50
- 75

an attachment to said envelope at said station while said cover-flap is open, said flap-opening means including an interference member adapted to be engaged beneath the leading edge of said flap in transit.

14. A machine for applying an attachment, such as a fastener and/or a patch, to an envelope with a cover-flap, in an operation to be performed while said cover-flap is open; said machine comprising in combination, means to supply envelopes with initially closed cover-flaps; an attachment-applying station; means to open the cover-flap of each envelope; and means to apply an attachment to each envelope at said station while said cover-flap is open; said flap-opening means including a sucker device adapted to be engaged with the outer face of said flap, and to cause divergence of the flap from the body of the envelope at the fold-line of said cover-flap and body.

15. A machine for applying attachments, such as fasteners and/or patches, to envelopes with cover-flaps, in a series of operations to be formed while said cover-flaps are open; said machine comprising in combination, an attachment-applying station; means to support a stack of envelopes assembled upon their closed bottom edges with their cover-flap ends extending upwardly; and means to separate the lowermost closed edge of each envelope from the stack, said separating means including a sucker device; means to advance each envelope upon such separation of its leading edge; means to open each cover-flap when the envelope is so advanced; means to apply an attachment to each envelope at said station; and means to accumulate said envelopes in stack form.

16. A machine for applying attachments, such as fasteners and/or patches, to envelopes with cover-flaps, in a series of operations to be formed while said cover-flaps are open; said machine comprising, in combination, an attachment-applying station; means to support a stack of envelopes assembled upon their closed bottom edges with their cover-flap ends extending upwardly; and means to separate the lowermost closed edge of each envelope from the stack, said separating means including a sucker device, means to advance each envelope upon such separation of its leading edge; means to open each cover-flap when the envelope is so advanced; means to apply an attachment to each envelope

at said station; and means to accumulate said envelopes in stack form, said opening means including another sucker device operating exclusively upon each cover-flap while the envelope is in transit.

17. In a machine for operating upon envelopes, in combination, means for supporting a stack of envelopes with their closure flaps folded, means for removing the blanks from the stack one by one including a rotary member arranged to grip the closed end of each blank, a suction device arranged to advance the closed end of each blank from its normal position in the stack to said rotary gripping member, and means including a thin, substantially flat plate adapted to engage the inner face of the flap for unfolding the closure flap of each blank as an incident of its removal from the stack.

18. A machine for applying an attachment to an envelope with a cover-flap, in an operation to be performed while said cover-flap is open; said machine comprising, in combination, an attachment-applying station; means to receive a supply of envelopes having initially closed cover-flaps; means to advance said envelopes toward said station; means to open each cover-flap while in transit to said station; means to apply an attachment to each envelope at said station while its cover-flap is open; means to advance the closed end of each envelope against a stop; means to advance each envelope in a predetermined path and means located adjacent said path for closing the flap of each envelope.

19. A machine as set forth in claim 18 in which said stop comprises a plurality of spaced apart guide areas and the means to advance each envelope comprises a flexible supporting member arranged substantially parallel to said stop.

20. In a machine for operating upon envelopes, in combination, means for supporting a stack of envelopes with their closure flaps folded, means for removing the blanks from the stack one by one including a rotary member arranged to grip the closed end of each blank, a suction device arranged to advance the closed end of each blank from its normal position in the stack to said rotary gripping member, an oscillatory sucker for unfolding the flap of each envelope as an incident of its removal from the stack and means for operating the sucker in timed relation with the means for removing the envelopes.

ABRAHAM NOVICK.
